FURNACE

Eugene Oscar Engels, Saginaw, Mich., assignor
to Baker Perkins Company, Inc., Saginaw,
Mich., a corporation of New York

Application October 13, 1934, Serial No. 748,190

3 Claims. (Cl. 158—1)

This invention relates to furnaces for heating 5
bake ovens, dry kilns, or the like by the circulation
of hot products of combustion through the oven,
either through radiating flues, or by mixing them
directly with the atmosphere of the oven. It has
to do more particularly with oil or gas-fired furnaces
consisting of a cylindrical tunnel having a
burner at one end and opening at the other end
into a tubular jacket which encloses it, through
which jacket the gases to be heated are drawn
or forced at high velocity.

In furnaces of this kind, especially when used
in systems which recirculate spent heating gases
from the oven over the combustion chamber where
they are mixed with fresh products of combustion,
it has been very difficult to provide a material
for the combustion chamber walls which will withstand
the extremely high operating temperatures. The costliest stainless steel cylinders lined
with refractory material have lasted only a short
time in regular service.

The object of this invention is to provide means
for cooling and protecting the combustion chamber
walls against intense heat of the gas or oil
flame within it, so that longer life will be assured
for the structure and its cost of construction and
maintenance will be reduced. The invention accom-
plishes this purpose by providing novel means
at the cylinder end of the cylindrical combustion
chamber for injecting into the combustion chamber
a rapidly moving helically-directed layer of
relatively cool inert gases. These gases form a
moving blanket over the inner wall of the cylind-
rical combustion chamber, cooling the wall by
convection and preventing erosion by contact
with the burner flame.

A further feature of the invention is that the
helically flowing layer of gases by its vortex effect
produces, or greatly increases, suction at the
fuel burner nozzle. This greatly improves the
efficiency of combustion and aids in a certain
automatic regulation of fuel and air supply, which
will be described further in this specification.

The invention by which these objects are at-
tained resides in the provision of a plurality of
openings spaced circumferentially of the com-
bustion chamber wall near the end at which the
burner is located, together with means for di-
recting inert gases such as recirculated flue gases
50 to be heated at high velocity circumferentially of
the combustion chamber. A portion of the inert,
relatively cool gases enters the combustion cham-
ber at high enough velocity to form a circum-
ferentially rotating blanket of inert gases which
55 sweeps the wall of the combustion chamber or

tunnel throughout its length, and surrounds and
encloses the burner flame, thus effectively cooling
and protecting the tunnel wall or its refractory
lining from direct contact with the burner flame.

A further feature of the invention may consist 5
of means for positively directing the jets of air
entering the combustion chamber so that the
flow of inert gases is given a definite helical travel
toward the discharge end of the chamber. Ordin-
arily, however, due to the suction usually pres- 10
ent in the chamber, produced either by positive
suction of the circulating fan, or by the entrain-
ment effect of gases passing its outlet at high
speed, the inert insulating gases while whirling
circumferentially of the combustion chamber as 15
indicated by the curved arrows in Fig. 2 are drawn
toward its mouth, so that they blanket the entire
inner wall.

These and other features of the invention are
described and illustrated in the accompanying 20
drawing in which,

Fig. 1 is a diagrammatic longitudinal section
of a furnace embodying my invention, and

Fig. 2 is a transverse section through the inner
end of the furnace, taken along line 2—2 in 25
Fig. 1.

The heating plant, shown in Fig. 1, comprises
a tubular jacket or furnace shell 1 which opens
into a heated duct 2 which in turn leads to the
inside of an oven or kiln 3. The hot gases from
duct 2 pass either directly into the oven atmos- 30
phere, or through radiating flues 4 shown in
dotted lines, and thence into an exhaust duct 5.
Duct 5 leads to a centrifugal blower 6 which
discharges through a duct 7 back into the jacket 35
1 at its closed end. This known structure forms
a closed circuit for the hot gases of combustion,
through which they circulate, giving up their
heat in the oven 3 and being continuously re-
heated in the jacket 1. So much of the gases 40
as is displaced by fresh products of combustion
is vented off through a damper regulated flue
7a leading to a suitable stack or other outlet to
the atmosphere.

To the above described structure my invention 45
is applied.

A cylindrical combustion chamber 8, open at
one end is mounted coaxially within and spaced
from the jacket 1. At the burner end the jacket
1 has a spiral portion 1a progressively increas- 50
ing in radius and tapering in width to the point
of connection with duct 7. The tangentially di-
rected duct is thus faired smoothly into the cy-
lindrical body of the jacket, and portion 1a de-
fines a spirally tapered duct surrounding the 55

5 combustion chamber at the burner end. The combustion chamber may or may not be lined with refractory material 9, depending upon the temperatures which are to be encountered in particular installations.

10 Spaced circumferentially of the closed end of the combustion chamber 8 in the outer wall thereof are a plurality of ports or openings 10. The inlet duct 7 is offset, as shown in Fig. 2, so that 15 the gases driven by the blower 6 enter the shell tangentially and are given a rapid travel circumferentially of the chamber past the ports 10. Jets of gas enter the combustion chamber 8 through ports 10 at high velocity and swirl rapidly 20 circumferentially of the interior of the combustion chamber. Due to suction produced by the induction effect of gas passing the open end of the combustion tunnel, the layer of swirling gases travels helically lengthwise along the inner 25 walls of the combustion chamber. As shown in Fig. 1, the gases may be further positively directed in the desired helical path toward the mouth of chamber 8 by beveling the refractory lining 9 where it is cut away adjacent to ports 10.

25 At the closed inlet end of the tunnel 8 a fuel burner 11 of known type, to burn premixed air and gas or oil, is installed to direct its flame lengthwise of the tunnel toward its open end.

30 Heretofore in furnaces of this general type a great deal of trouble has been caused by the extremely high temperatures to which the combustion chamber walls were subjected. Expensive alloy steels lasted only a short time under the extreme conditions, and the best refractory lining 35 speedily disintegrated. This invention eliminates that difficulty and permits of the construction of the furnace from relatively inexpensive materials.

35 In operation, the inert, relatively cool recirculated gases of combustion are supplied at high 40 velocity from duct 7, are given a rapid movement circumferentially of the outside of the cylindrical combustion chamber. Due to their circular travel and relatively high pressure a portion of them 45 flow tangentially into the combustion chamber through ports 10, being so directed by the progressively reduced diameter of the spiral portion 1a of the jacket enveloping the combustion chamber. Here by reason of their high speed, they 50 form a helically rotating layer of gas, wiping and cooling the inner wall of the combustion tunnel and enclosing as in a tube of gas the axially directed burner flame. In addition to cooling 55 the wall by convection the tubular layer of inert or incombustible gases also protects the wall from oxidation or reduction by direct contact with the burner flame.

60 A further advantage of my invention in a furnace as shown is that it facilitates the use of a small atmospheric type fuel burner, eliminating expensive and complicated pressure regulating devices for the fuel or combustion air.

65 In a recirculating system as shown it is desirable to use an atmospheric burner for the further reason that suction at the outlet of the combustion chamber and the entraining effect of the circulated gases varies inversely with their temperature. Thus, with a relatively small flame a high degree of automatic heat regulation is obtained. For example, when the heating gases are 70 cooled below the desired temperature, their density increases. The suction in the combustion chamber immediately increases, and additional fuel and air are drawn into the burner to increase the rate of combustion.

75 My invention enhances this effect by greatly increasing the suction normally prevailing within the combustion chamber around the burner nozzle, and increasing its range of variation with changes of temperature and density of the circulating gases. This increase in suction is brought about by the vortex effect of the layer of gases swirling at high velocity circumferentially of the chamber wall.

80 While I have shown my improved apparatus applied to a recirculating oven-heating system, it is not limited to such application. For example, it may be used in heating systems for dry kilns, drying tunnels, etc., in which the spent gases are not recirculated, but are discharged directly to a 85 stack. In such an installation sufficient relatively cool inert gases may be bypassed from the stack to the blower 6 to produce the desired cooling and protection of the wall of the combustion tunnel. This, and other modifications in 90 the use of the apparatus embodying my invention may be made without departing from the scope of the appended claims.

95 From the foregoing, it will be seen that in the operation of my device the burner flame made of a combustible mixture of air and gas or oil is blown axially lengthwise of the combustion chamber or tunnel 8, and that the burner flame is surrounded by an annular layer of burnt, spent, or inert gases, indicated at 12, in the form of a 100 helically swirling film or layer that follows around the inner wall of the combustion chamber from the ports 10 to the end of the chamber. The burner flame is separated from the inner wall of the chamber by this protective gaseous layer. 105 Due to the high rate of travel of the layer the inner wall, or the inner lining, of the combustion chamber is protected from the deteriorating effect of the high temperature burner flame, and 110 consequently the life of the combustion chamber is greatly increased.

115 Having thus described my invention, what I claim and desire to secure by Letters Patent is:

1. In a furnace, in combination, a cylindrical 120 combustion chamber open at one end, a fuel burner mounted in its other end directed axially of said chamber, and a jacket surrounding said chamber and spaced therefrom, a source of inert gases, a conduit connecting said source of inert 125 gases and said jacket, means for impelling gases from said source at high velocity therethrough, said conduit joined to said jacket adjacent the burner end thereof and directed tangentially of said combustion chamber to direct said inert 130 gases circumferentially of the exterior of said chamber, the wall of said combustion chamber adjacent its burner end being provided with ports 135 therethrough to admit a portion of said circumferentially moving gases to the interior of said combustion chamber to form a helically traveling layer of inert gases over the inner peripheral surface thereof.

140 2. Apparatus as claimed in claim 1, wherein the jacket adjacent the burner end of the combustion chamber includes a spiral peripheral wall portion connected to the conduit, having its maximum radius at said connection and at its minimum radius merging into the cylindrical wall of said jacket to define a gas passage encircling the cylindrical combustion chamber in 145 which the clearance between the said spiral wall portion and the outer wall of said combustion chamber is progressively reduced circumferentially of said chamber.

3. In a furnace, in combination, a cylindrical combustion chamber open at one end and a fuel burner mounted in the other end directed axially of said chamber, the peripheral wall of said combustion chamber adjacent the burner end being provided with openings therethrough, a source of inert gases, conduit means leading from

said source of inert gases to said combustion chamber openings, means for impelling gases therethrough, and means for directing said gases tangentially into said combustion chamber to form a helically traveling layer of said gases over 5 the inner peripheral wall thereof.

EUGENE OSCAR ENGELS.
